UNITED STATES PATENT OFFICE.

SAMSON E. FOLKINS, OF LONG ISLAND CITY, NEW YORK; SARAH F. FOLKINS ADMINISTRATRIX OF SAID SAMSON E. FOLKINS, DECEASED.

IRONING CABINET.

Application filed November 5, 1926. Serial No. 146,529.

This invention relates to an ironing cabinet and has for one of its objects the production of a space saving or utilizing unit for homes wherein easily accessible storage space for 5 ironing boards and clothes racks or dryers is not otherwise provided for.

It is also an object of the invention to so arrange an ironing cabinet that an ironing board may be snugly and rapidly stowed 10 therein when out of use, and may be instantly extended therefrom and adjusted to the desired height for use with but little effort on the part of the user.

Another object of the invention is to so arrange an ironing cabinet that a clothes rack may be housed therein, and adjustably mounted for positioning to various heights and located directly over the ironing board whereby the heat arising from the iron and 20 the board aids in the drying of the previously ironed clothes which may be hung on the rack.

Another object of the invention is to so arrange the ironing board with respect to the pivot upon which it swings that it may be positioned at any point between the maximum and minimum heights of adjustment, and retain its self in such position thus obviating the actual necessity of the aid of counter balance weights which however are used merely 30 to lighten the efforts of the user in adjusting the board into position.

Other objects of the invention will be fully understood from a description of the drawings and the claims hereinafter given.

35 Of the drawings:

Figure 1 represents a front elevation of the cabinet as it appears when closed.

Figure 2 is a view similar to Figure 1 but showing the cabinet open and ready to have 40 the clothes rack and ironing board presented for use.

Figure 3 is a section on the line 3—3 Figure 1 showing the rack and ironing board in elevation.

45 Figure 4 is a view similar to Figure 3 but showing the rack and ironing board extended for use.

Figure 5 is an enlarged front elevation of 50 portions of the upper part of the cabinet showing a portion of the rack, and the pivotally and vertically sliding mounting therefor.

Figure 6 is a section on the line 6—6 Figure 4 showing the pivotal and sliding mount-

ing for the rack which is omitted therefrom. 55

Figure 7 is a section on the line 7—7 Figure 4.

Figure 8 is an enlarged section through a portion of the inner end of the board showing the relative positions of the board and 60 its pivot.

Like characters represent like parts throughout the several figures of the drawings.

The drawings herewith illustrate a convenient and economical form of ironing cabinet which is so arranged as to be secured to an existing wall or built therein during the construction thereof.

The cabinet is comprised of the top and 70 bottom boards 10 and 11 respectively, the side walls 12 and 13, and the rear wall 14, a shelf or partition 15 being arranged approximately midway of the cabinet to form two compartments 16 and 17 the upper one 75 of which may be closed from entrance by the narrow doors 18 and 19 co-acting with a pivotally mounted board 20 to be later described, and the lower compartment by the large door 21, suitable fastening means being employed 80 to retain them in closed position.

The side walls of the lower compartment are provided with grooves 22 to receive the shoes 23 to which is pivoted a cleat 24 which is secured to the top side of the ironing 85 board 25 at the inner end thereof.

When the board 25 is extended as seen in Figure 4 of the drawings the inner end thereof is in contact with the rear wall 14 of the cabinet, and its pivot 26 is so located with respect 90 to it that the weight of the board automatically frictionally locks it in any position in which it may be left.

The board 25 however is provided with a prop or support 27 which is hinged to a cleat 95 28 at the under side of the board, and held in position as seen in Figure 4 by a cord or other flexible material 29 which readily collapses when the board is to be stowed as seen in Figure 3 of the drawings.

When weight is applied to the board 25 its inner end will be forced, in the arc of a small circle, to frictionally grip the rear wall 14 of the cabinet, while the prop 27, because of its angular relation with the board 25 and 100 wall 27, will frictionally grip the said wall also thus sustaining the weight on the said board and maintaining it in its set position.

In order to relieve the user of the expenditure of unnecessary energy when adjusting the board to extended position a counter balance weight 30 is employed.

5 The said weight 30 is arranged to travel in grooves 31 and 32 of the face board 33 and rear wall 14 respectively of the upper compartment 16, and has cord connection with each of the shoes 23, the said cord passing to 10 the pulleys 34 and 35 to the left of the compartment and another cord passing over the pulleys 36 and 37 to the right of the compartment, the said cords being housed in grooves 38 and 39 in the side walls 12 and 13 respectively which are extensions of the grooves 22 of the side walls of the lower compartment.

15 The upper compartment 16 normally houses a clothes rack 40 of well-known construction mounted on a pivoted panel or board 20 which has a pivot pin 41 mounted in the shelf 15 and a hollow or tubular pivot 42 engaging the cleat 43 at the top of the opening 44 of the said compartment.

20 The said panel 20 has inwardly facing grooves 45 at the inner faces or edges of the side cleats 46 which retain the board 47 in place, and guide it in its vertical movements.

25 The said board 47 has a cleat 48 at the top, and a cleat 49 at the bottom thereof between which is arranged a rod to be hereinafter referred to.

30 The rack 40 normally pivotally depends from the underside edge of the cleat 48 by means of the hook and eye connections 50 between it and the plate 51 to which the rack arms 52 are pivoted as usual but may be swung upwardly to assume the position shown in Figure 4 after the panel 20 has been given a half turn on its pivots 41 and 42 to thereby 35 cause the said rack to first face outwardly.

40 When the rack is in stowed position the arms 52 will be bunched and pressed between the spring fingers 53 which retain them in a yieldingly locked position.

45 Preferably a handle 54 is attached to the board 47, and depending therefrom, and within the reach of the user whereby the board 47 and consequently the rack 40 may be adjusted into the desired height.

50 After the panel 20 has been swung so that the rack 40 faces outwardly the doors 18 and 19 may be closed and as they then overlap

the panel, rotary movement thereof is thereby prevented.

55 Unlike the ironing board 25 the board 47 is not frictionally held in any position to which it may be moved but may be instantly moved up or down and will be retained in any given position by means of the counter balance weight 55 which is guided in grooves 56 and 57 formed in the rear wall 14 and front board 58 respectively.

60 The said weight 55 is hung from a cord 59 attached to the board 47 and passes upwardly through the hollow pivot 42 over the pulleys 60 and 61 to the weight, which arrangement permits of rotary movement of the board 47 with the panel 20 which may be swung about the pivot 42 containing the cord.

65 As previously stated the rack 40 is of well known construction being arranged to swing upwardly and to be held in that position by a bail like prop or support 63 which is forced to engage shoulders 64, of a plate 65 fast with the board 47, by the spring rod 66 which 70 normally keeps the prop in close contact with the said board.

75 Viewing Figure 4 it will be seen that a portion of the ironing board 25 is indicated in two of the many horizontal planes it may 80 be made to occupy, which is also true of the rack 40 as evidenced by the two dotted line positions of the arms 52.

Having described the invention I claim:

85 1. An ironing cabinet having an opening therein for the stowage of a collapsible clothes rack, said rack being mounted on a board arranged to slide in vertical guideways of a panel, said panel being arranged to be pivotally mounted at the opening of said cabinet, 90 doors hinged to said cabinet, one on each side thereof, and arranged to partly overlap said panel whereby they restrain said panel from pivotal movement when they are in closed position.

95 2. A device as claimed in claim 1, wherein the doors are engageable with the panel when either face thereof is outwardly disposed and the opposite face of the door of the panel from said bracket has means coacting with 100 the doors to present a smooth finished surface.

Signed by me at Boston, Massachusetts this 29th day of October, 1926.

SAMSON E. FOLKINS.
